DRY SHAVER WITH ABRADER

Guillaume Barsch, Geneva, Switzerland

Application January 10, 1946, Serial No. 640,153
In Switzerland February 19, 1945

14 Claims. (Cl. 30—34)

1

The dry-shaving apparatuses in current use present the drawback of not cutting the beard as closely as other types of razors comprising a blade for directly cutting the beard moistened or lathered beforehand. This is owing to the fact that these dry-shaving apparatuses operate like clippers and not like razor blades.

The present invention aims at obviating this drawback and relates to a dry-shaving apparatus, which is characterised in that it comprises, besides means for cutting the beard, associated means for abrading the part of the "bristles" that have just been cut and which still projects above the surface of the skin, this being done at the same stage of working as the actual cutting.

The annexed drawings represent, in the way of examples, two embodiments of the dry-shaving apparatus according to the invention.

Figure 1 is a view in partial axial section of the first embodiment;

Figure 2 is a side view corresponding to Figure 1;

Figure 3 is a plan with a semi-section according to III—III of Figure 1;

Figure 4 is a partial view in elevation of the second embodiment;

Figure 5 is a similar view to Figure 4, but in partial median section;

Figure 6 is a cross-section on the line VI—VI of Figure 5;

Figure 7 is a cross-section on the line VII—VII of Figure 5.

The apparatus represented by Figures 1 to 3 includes:

A holder base 1 only the end of which is seen and which contains a revolving motor, preferably an electric motor.

The end of the shaft of this motor is visible at 2. On the terminal part 3 of this shaft 2 a set collar 4 is permanently fixed and, against this collar a revolving body 5 is fixed in a detachable manner on the part 3. This body 5 is placed inside an independent casing 6, which fits in a bayonet-socket at 7 on to the base 1.

An opening 8 is provided in the region of the casing 6 where the revolving body 5 is situated.

The revolving body 5 is in stone of the whet-stone type and has a cylindrical revolution shape. On the periphery of the body 5, a channel 9 is provided, extending parallel to the axis of this body and in which a metallic U-shaped part 10 is lodged, the median portion 11 of which forms a grid with parallel slits. The grid 11 projects beyond the lateral surface of the cylindrical stone 5. The direction of rotation of this stone is indicated

2

by an arrow in Figure 3. It is seen in the same figure that the front edge of the grid 11 is situated at a shorter radius than its rear edge.

The apparatus represented comprises also a cutting-blade 12 presenting an elbow at 13 and the cutting-end of which is indicated at 14. At its opposite end, the blade 12 presents a bent part 15 which fits into a corresponding slit in the casing 6 for detachably fixing it on this casing, as is seen in Figure 3. The part of the blade 12 included between the end 15 and the elbow 13 has a less pronounced curvature than the cylindrical casing 6 (Figure 3). The free end of the blade 12 passes through the opening 8 to co-operate with the grid 11, as is described farther on.

Around the casing 6 is placed a metallic ring 16, slightly flexible, extending over about two-thirds of the periphery of this casing 6. This open ring presents, at each end, a bent-back part 17 and 18 respectively allowing it to be turned around the casing 6 with the fingers, concentrically to the axis of the apparatus, with the object that is indicated below. Near its part 18, the ring 16 presses the blade 12 against the casing 6, thus keeping the part 15 lodged in the corresponding slit in this casing. It is easily understood that making the ring 16 turn in either direction (Figure 3) regulates the position of the cutting-edge 14 in relation to the revolving body 5 and regulates at the same time the force with which this cutting-edge is pressed against the grid 11 when the latter passes in front of it.

The apparatus described operates as follows:

When the motor (not shown) revolves, turning with it the revolving body 5, and when the part of this revolving body appearing in the opening 8 is brought into contact with the surface to be shaved, this is what happens:

As is known, the co-operation of the grid 11 and the cutting-edge 14 cuts the beard, the "bristles" of which, at the moment when this grid passes in front of the cutting-edge, are engaged in the slits of this grid. However, as in the current type of dry-shaving apparatus, after this operation, there remains a part of the "bristles" which projects beyond the surface of the skin; cutting-members being always of a certain thickness, the dry "bristles" cannot be severed level with the surface of the skin. When the grid 11 is no longer in contact with the skin, after having co-operated with the cutting-edge 14, it is the surface of the stone 5 which comes in contact with the region of the skin that has just been shaved. This stone then acts as an abrasive which rubs away the part of the "bristles" that have just been cut and which

3

still projects beyond the surface of the skin. This projecting part of the "bristles" is thus eliminated, and this is done at the same stage of working as the actual cutting since, in the course of the successive rotations of the revolving body, there is alternately a cutting operation and an abrading one.

The end 19 of the revolving stone 5 protrudes beyond the casing 6 and presents a convex surface, as is seen in Figures 1 and 2. This part 19 can therefore be brought in contact with the surface of the skin which has just been shaved if by any chance the abrasion of the beard has been insufficient.

Obviously, in Figure 3, the extent to which the grid 11 has been made to project beyond the surface of the revolving stone 5 is exaggerated so as to make the drawing clear. Besides, it is naturally provided for that the cutting-edge 14 should never come into contact with the surface of the stone.

A sleeve 20 is mounted for sliding on the shaft 2. This sleeve is integral with a propeller 21, the role of which is about to be indicated. The sleeve 20 is integral with a coupling member 22 with ratchet teeth, intended to co-operate with a similar element 23 fixed on the shaft 2. A compression spring 24 induces the elements 22 and 23 to stay separate, as is seen in Figure 1. One end of the spring 24 bears against the base 1 and the other against a disc 25 with a milled edge, as indicated at 26. The disc 25 is intended to move axially with the sleeve 20 without participating in its rotation. Openings 27, 28 cut in the casing 6 allow of taking hold of the disc 25 by its periphery to move it axially towards the position in which the elements 22 and 23 are engaged. The instant this coupling takes place the propeller revolves and blows out the beard clippings that may be under the grid or inside the casing 6. As soon as the disc 25 is released, the spring 24 brings it back into the position shown in which it is pressed against languets 29 punched in the casing 6.

It is understood, of course, that the grid may comprise, not suits, but circular or triangular-shaped openings, for example.

The apparatus represented in Figures 4 to 7 comprises a body 31 inside which is an electric motor not visible in the drawing. This body 31 bears a detachable head 32, the cylindrical top 33 of which presents a zone 34 provided with narrow openings 35 formed by a series of small slits and another zone 36 provided with openings 37 larger than the openings 35.

Inside the head 32 a mobile mechanism revolves, driven by a shaft 38 itself driven by the motor enclosed in the body 31. The head 32 is fixed on to the body 31 by means of a bayonet-socket 39.

The revolving mechanism comprises a part 40, fixed to the shaft 38 by a pin 41. This part possesses two radial slots 42, diametrically opposite, as is seen in the drawing. In each of these slots 42 a blade-holder 43 is mounted so as to oscillate; this blade-holder possesses a hook cooperating with an axis 44. A circular clip 45, placed round the part 40, keeps the blade-holders 43 on this part, while allowing these holders to be detached at will, for which it is sufficient to shift the circular clip 45 downwards in Figure 5.

Each of the blade-holders 43 includes a clamp 46, mounted so as to oscillate on it at 47. Each of these clamps 46 grips between its two arms a rectilinear-shaped cutting-blade 48.

4

It is easily understood that, under the influence of the centrifugal force acting on the blade-holder 43, the clamp 46 and the blade 48, and which is due to the rapid rotation of the shaft 38, each of the cutting-blades 48 is impelled outwards and revolves with its cutting-edge in contact with the inner surface of the casing 33, as is seen on the right-hand side of Figure 7. The upper end (according to Figure 5) of each of the cutting-blades 48 presents a portion 49 which, when the blade passes in front of the zone 36 with the large openings 37, co-operates with a surface 50 on the inside of the head 32 and this obliges the said blade to recede from these openings towards the axis of rotation. The surface 50 is of a cylindrical shape, but is situated at a shorter distance from the rotation axis than the inner surface, also cylindrical, of the head 32 (Figure 6).

The revolving mechanism comprises also an abrading member consisting of a stone 51 presenting two parts 52, 53, in the form of cylinder sectors. The two cylindrical portions of the lateral surface of the abrading member 51 revolve in the immediate proximity of the inner surface of the head 33, as is seen in Figures 6 and 7.

The dry-shaving apparatus represented in Figures 4 to 7 works as follows:

When the shaft 38 revolves, driving with it the cutting-blades 48 and the abrading member 51 in the direction of the arrow 54 (see Figure 7), each of the blades 48 successively passes, for every revolution of the shaft, in front of the zone 34 with the small openings 35 and the zone 36 with the large openings 37. During its passage in front of the zone 34, this blade, in co-operation with these openings, cuts the hairs of the beard engaged in these openings when the zone 34 is applied against the part of the face that is to be shaved. On the other hand, when the blade 48 arrives in front of the zone 36 with the large openings 37, it is automatically made to recede from these openings by the surface 50 and this precludes any possibility of contact between the skin and these blades through these large openings 37.

Moreover, with every revolution of the shaft 38, each of the parts 52, 53 of the abrading member successively passes in front of the zones 34 and 36 of the head of the apparatus. When the abrading member passes in front of the zone 34, it has no effect, whereas, when the parts 52 and 53 of the member 51 successively pass in front of the large openings 37 of the zone 36, they abrade the hairs of the beard that have just been cut on that part of the face against which this zone 36 is applied. The dimensions of the openings 37 are, in fact, large enough for the skin to come into contact across them with the abrading member when the zone 36 is applied against the face.

It is thus understood that, when the shaving apparatus is held in the hand, either the zone 34 or the zone 36 can be brought, with a very slight movement of the hand, into contact with the surface to be shaved, contact with the zone 34 producing the cutting of the hairs of the beard and contact with the zone 36 the abrasion of what remains of the hairs that have just been cut.

It will be observed, in examining the drawing, that the zones 34 and 36 are contiguous and that they together extend over an angle of less than 180°. The angle within which the pair of zones 34 and 36 is confined may with advantage

be less than 120° so as to limit the movement of the hand necessary to pass from the cutting operation of the hairs of the beard to that of their abrasion, and vice versa.

What I claim is:

1. A dry shaving apparatus comprising a cutter, means for presenting to the cutter only an extreme portion of each bristle, and abrading means associated with the cutter for abrading the portion of bristle intermediate said extreme portion and the skin of the user.

2. A dry shaving apparatus comprising a cutter including a stationary blade and means for presenting to the blade only an extreme portion of each bristle including at least one revolving grid and abrading means for abrading the portion of the bristle intermediate said extreme portion and the skin of the user including at least one abrading member revolving with said grid.

3. A dry shaving apparatus comprising a stationary blade and a revolving body of a generally cylindrical shape including a grid and at least one abrading member mounted on the lateral surface of said body.

4. An apparatus as claimed in claim 3, further comprising a casing, said body revolving inside said casing, and said casing being provided with a lateral aperture through which the surface to be shaved comes into contact with the lateral surface of said revolving body.

5. An apparatus as claimed in claim 4, said cooperating blade being constituted by a metallic member having on one side thereof a part adapted for detachably connecting to said casing and a cutting edge on the other side thereof adapted to penetrate through said lateral aperture and to cooperate with said grid.

6. An apparatus as claimed in claim 5, said metallic member having an offset portion adjacent said cutting edge, the portion of said member intermediate said offset portion and said connecting part having a greater radius of curvature than said casing, said apparatus further comprising a resilient annular member surrounding the major segment of said casing and encompassing said cutting blade, said annular member being slidably rotatable around said casing to encompass and apply resilient pressure

to selectively greater and lesser areas of said cutting blade intermediate said offset portion and said connecting part, whereby the amount of cooperation between said grid and said cutting edge may be adjusted.

7. An apparatus as claimed in claim 3 wherein in one end of said revolving body protrudes beyond said casing, said protruding end having a convex surface at least partly formed by said abrading member.

8. An apparatus as claimed in claim 2 wherein in said abrading member is of stone.

9. A dry shaving apparatus comprising a head, at least one cutting blade and at least one abrading member mounted for rotation inside said head, the lateral wall of said head being provided with a first zone of narrow apertures cooperating with said cutting blade to cut the beard and with a second zone of relatively larger apertures cooperating with said abrading member, the apertures of said second zone being large enough to enable the skin to come into contact therethrough with the surface of said abrading member.

10. An apparatus as claimed in claim 9 including means disposed inside said head and connected thereto and means connected to said cutting blade, whereby in course of rotation said cutting blade will be constrained to recede from said second zone and pass across said larger apertures without contacting the skin.

11. An apparatus as claimed in claim 9 wherein in said first and second zones are contiguous.

12. An apparatus as claimed in claim 11 wherein said two zones are contained in an arc of 180°.

13. An apparatus as claimed in claim 9, including a blade holder adapted to oscillate in a plane radial to the axis of rotation of said cutting blade, said cutting blade being mounted in said holder, whereby said blade and holder during rotation will be impelled by centrifugal force against the inner surface of said head.

14. An apparatus as claimed in claim 9 wherein in said abrading member is of stone.
